Leicester Bradford,
ATTORNEY.

UNITED STATES PATENT OFFICE.

ANDREW L. HENRY, OF LADOGA, INDIANA.

SYRINGE.

SPECIFICATION forming part of Letters Patent No. 634,108, dated October 3, 1899.

Application filed August 20, 1898. Serial No. 689,075. (No model.)

To all whom it may concern:

Be it known that I, ANDREW L. HENRY, a citizen of the United States, residing at Ladooga, in the county of Montgomery and State 5 of Indiana, have invented certain new and useful Improvements in Syringes, of which the following is a specification.

This invention relates more especially to the nozzles or discharging portions of syringes; 10 and it principally consists in making such nozzles of small metal tubes bent at a central point with the two sides arranged in a substantially parallel relation, the discharge-ori- 15 fices being near the bend on the inner or ad- jacent sides of the tube portions.

Referring to the accompanying drawings, 20 which are made a part hereof and on which similar letters of reference indicate similar parts, Figure 1 is a top or plan view of a syr- 25 inge embodying my said invention; Fig. 2, a side elevation of the same; Fig. 3, a horizontal sectional view, on an enlarged scale, of the nozzle portion, the central part thereof being broken away; and Fig. 4, a detail sec- 30 tional view on the dotted line 4 4 in Fig. 3, but on a still further enlarged scale.

In said drawings the portions marked A represent the cylinder of an ordinary syringe, B the piston thereto, and C the nozzle embody- 35 ing my present invention.

The present invention relates solely to the nozzle portion, and the cylinder A and piston B are shown merely to illustrate a complete structure, and I desire it to be expressly understood that any other syringe structure or 40 body capable of supplying a fluid to the nozzle may be employed without departing from my invention.

The nozzle C, as hereinbefore stated, is 45 composed of a tube of suitable size and ma- terial bent at a central point, which point be- comes the extreme end of the nozzle, the tube being doubled upon itself, so that the por- tions on each side of said central point are 50 brought into a substantially parallel relation to each other. The bent portion of the tube beyond the orifices should be filled solidly, as shown at a, so that there shall be no cavity beyond said orifice within which sediment 55 might gather. The rear ends are connected to a suitable union-piece C', said union-piece being attached in a similar manner as other

nozzles are (or in any desired manner) to the fluid-supplying portion or body of the syr- 55 inge. Near the extreme point in the adjacent sides or facing portions of the tube are perforations c, which are preferably arranged exactly opposite each other. This arrange- 60 ment insures that the streams shall operate upon each other to create a fine spray, which is thus discharged laterally in substantially all directions from the point of the nozzle. The space between the two tubes forms a 65 passage-way for the outflow of the fluid. The perforations being thus arranged between the tubes are protected from contact with the 70 parts while the instrument is being inserted and withdrawn, and are thus free from the danger of gathering diseased matter or becoming clogged thereby.

Among the other uses to which my syringe is especially adapted is the insertion and satu- 75 ration of absorbent material within the parts to be treated. In doing this work the absorb- ent material is placed upon the point of the syringe-nozzle in such quantity and form as 80 may be desired, and the syringe having previously been charged with the desired satu- rating liquid or medicament the material is forced into place by the point of the nozzle, and said liquid is afterward discharged into 85 the said absorbent material, saturating it from the center outwardly. Strong medica- 90 ments may thus be applied directly to the diseased parts, where desired, without previ- 95 ously coming in contact with any of the parts which must be passed in reaching such diseased parts. The discharge of fluid being lateral and being prevented by the form of the nozzle from passing beyond the end of 100 said nozzle, all danger of forcing the liquid beyond the point desired is obviated.

The fine hollow tubes of which the nozzle is composed are flexible in a high degree and may be bent in almost any form desired, so 95 that the course and direction may be adjusted from time to time as the exigencies of any case may require, while obviously the nozzles may be made of widely-varying lengths, so as to penetrate to any desired depth. A phy- 100 sician having a syringe with a set of these nozzles of varying sizes and lengths is enabled to conveniently do much work which has heretofore been regarded as very difficult.

Having thus fully described my said invention, what I claim as new, and desire to secure by Letters Patent, is—

The combination with the body of a syringe, 5 of a nozzle therefor composed of a doubled tube arranged with the bend at its outer end and its open ends united in a coupling or socket-piece attached to the body of the syringe with which both ends are thus made to 10 communicate, a discharge-orifice being formed in each branch in their adjacent sides near

the outer end just behind the bend, said bend being filled or made solid beyond said orifices, substantially as set forth.

In witness whereof I have hereunto set my 15 hand and seal, at Indianapolis, Indiana, this 9th day of August, A. D. 1898.

ANDREW L. HENRY. [L. S.]
